LUMINOUS TUBE CONNECTION DEVICE

Application filed February 10, 1930. Serial No. 427,226.

This invention relates to a device for leading electrical energy into a luminous tube, such as are now in common use for signs and advertising purposes. These tubes usually 5 comprise a filling of a noble monatomic gas at low pressures, arranged to be rendered luminous by the passage of an electric current through the gas.

Often such tubes are supported on the exterior of a box structure, which forms a support for the tubes. Since the potential differences used to energize the tubes are of the order of thousands of volts, it is necessary 10 that the wires leading to the tube be very heavily insulated. Such insulated wires are 15 stiff and cannot be bent at sharp angles.

It is one of the objects of my invention to provide a connector in which the wires can be led to the tube straight, thereby reducing 20 the space required for housing the wiring, and making the completed sign more compact. The insulation clearances are also improved.

My invention possesses many other advantages, and has other objects which may be made more easily apparent from a consideration of one embodiment of my invention. For this purpose I have shown a form in the drawing accompanying and forming part of 25 the present specification. I shall now proceed to describe this form in detail, which illustrates the general principles of my invention; but it is to be understood that this detailed description is not to be taken in a 30 limiting sense, since the scope of my invention is best defined by the appended claims.

Referring to the drawing:

Figure 1 is a sectional view of a portion of a sign box structure showing my device in 40 use;

Fig. 2 is a top plan view of the connector; and

Fig. 3 is a detail section of the resilient socket portion of the device.

In Fig. 1, there is shown a portion of a box structure 11 within which the wiring and the transformers for the luminous tubes, such as 12, are supported thereon. This structure is shown as having a bottom 13, the 45 depth of the box being kept as small as possi-

ble. The tubes 12 supported on the box each have an end 14, extending into an insulating connector device 15.

This device 15 is preferably made from ceramic material, such as porcelain. It has a tubular portion 16 into which the end 14 extends. This portion 16 can extend through an aperture in the top of the box 11, and can be fastened to the top as by screws 5 17 passing through the ears 18.

The end 14 of the tube 12 carries a metallic cap 19 (Fig. 3), by the aid of which current can be led into the tube. This cap is resiliently held in a spring socket of suitable design, which is located in the bottom of the tubular portion 16. In the present instance, this spring socket is formed by a pair of resilient metal strips 20, 21 of U-shapes. The legs of the U are reversely bent to form the opposed spring fingers 23 engaging the cap 19. The strips 20, 21 are held together at their ends as by a screw 24 which also serves as a terminal post.

A cable or wire 25, heavily insulated, extends to the screw 24 to lead current thereto. 75 A right angle extension 26 leading from the tube 16 and integrally formed therewith, serves to protect and insulate the current carrying parts from the box 11. The spring socket 20-21 need not be fastened to the device 15, since the wire 25, in conjunction with the tube 12, keeps it in place.

It is to be noted that the connecting wire 25 leads to socket device 20, 21 in a straight line, without the necessity of bends or twists. Furthermore, the extension 26 is long enough to provide ample creeping distances for any leakage currents.

A resilient washer 27 can be used to cover 80 the tube 16 and to make it weatherproof.

I claim:

1. In a device for leading current to a luminous tube, a tubular body made from insulation material, a spring socket resting on the bottom of the body and in position to be engaged by the end of a luminous tube, said socket having a terminal post, said socket being unattached to the body, and a radial tube extension extending from the body near the bottom thereof, for shielding a connecting 95 100

wire to the post, said extension being long enough to provide a long creeping surface for leakage currents.

2. In a device for leading current to a luminous tube, a tubular body made from insulation material, a spring socket resting on the bottom of the body and in position to be engaged by the end of a luminous tube, said socket having a terminal post, and an integrally formed right-angled extension from the tubular body for shielding a connecting wire to the post, said wire being unrestrained by said extension for transverse movement therein.

15 3. In combination, a tubular body made from insulation material, said body adapted to be secured to the top of a box structure so that the bottom of the former is spaced from the bottom of the latter, a spring socket resting on the bottom of the body and in a position to be engaged by the end of a luminous tube, said socket having a terminal post, said socket being unattached to the body, and a radial tube extension extending from the 20 body near the bottom thereof for shielding a connecting wire to the post, said extension loosely surrounding the connecting wire and being long enough to provide a long creeping surface for leaking currents.

25 30 In testimony whereof I have hereunto set my hand.

WILLIS O. PROUTY.
